UNITED STATES PATENT OFFICE.

FREDERICK L. MACDONALD, OF WALTHAM, MASSACHUSETTS, ASSIGNOR TO FLOSTIK COMPANY, OF WALTHAM, MASSACHUSETTS, A CORPORATION OF MASSACHUSETTS.

DESIGN FOR A CASING FOR A DENTAL FLOSS HOLDER.

Application filed February 28, 1922. Serial No. 937. Term of patent 14 years.

To all whom it may concern:

Be it known that I, FREDERICK L. MACDONALD, a citizen of the United States, residing at Waltham, in the county of Middlesex and State of Massachusetts, have invented a new, original, and ornamental Design for a Casing for a Dental Floss Holder, of which the following is a specification, reference being had to the accompanying drawing, forming a part thereof.

The figure is a perspective view of a casing for a dental floss holder showing my new design.

I claim:

The ornamental design for a casing for a dental floss holder as shown.

FREDERICK L. MACDONALD.
